OVERHEAD DOOR STRUCTURE

Guy V. Smith, Marion, Ind.

Application July 12, 1938, Serial No. 218,856

1 Claim. (Cl. 16—104)

This invention relates to improvements in sectional door structures and means for facilitating the opening thereof, particularly the heavy types of doors used in garages, warehouses, gasoline service stations, etc., where the door is raised to an overhead position.

The primary object of the present invention is to provide a sectional door adapted, when shifted, to move to a substantially horizontal overhead position, wherein new and novel means of counterbalancing and new means for weather tightness is provided.

The invention will be best understood from a consideration of the following detailed description taken in connection with the accompanying drawings forming a part of this specification, with the understanding, however, that the invention is not confined to any strict conformity with the showing of the drawings, but may be changed or modified so long as such changes or modifications mark no material departure from the salient features of the invention as expressed in the appended claim.

In the drawings,
25 Fig. 1 is a rear or inside perspective view of the door in closed position.

Fig. 2 is a vertical sectional elevation at one end of the door in closed position.

Figs. 3, 4 and 5 are details in elevation and section of the track and the carriers which run therein.

Fig. 6 is a rear perspective of the door in open position.

Fig. 7 is a detail of a modification.

Fig. 8 is a perspective of a set of carriers.

Referring specifically to the drawings, A indicates the door jambs and B is the ceiling or other support for the upper part of the tracks

40 which are fixed at opposite sides of the doorway to the bottom of the jambs by brackets 7a and may be supported at the top in any suitable manner, as by a frame 10a below the ceiling.

As shown in Fig. 5 each track is flanged to retain the carriers which travel therein, as hereinafter described. It will be noticed that the tracks include horizontal and vertical sections connected by curved portions, and the vertical sections incline toward the door jambs at the bottom, to give a wedging action to the door

45 when closed.

The door is indicated at 17, and consists of a plurality of horizontal sections hinged together by end hinges 22 and (if desired) by middle hinges 22a. These sections run between the

tracks, and when the door is closed they wedge or are pressed against the jambs, and retract therefrom when the door is opened, in consequence of the inclination of the vertical sections of the tracks, and the construction of the carriers.

Each carrier comprises a plate 13, running edgewise and endwise beside the track, on wheels or rollers 19 which run in the tracks and are mounted on pins 20 projecting at opposite ends 10 and at one side of the plate 13. At or about the middle thereof the plate 13 is provided at the opposite side with a hinge pin 21 which forms the pintle of the hinge 22. To accommodate the inclination of the track, the distances of the hinge pintles 21 from the line of travel or edges of the plates 13 is varied (at each edge of the door) to agree with the variation of the space between the track and the door jambs. This is illustrated in Fig. 8. Obviously, in order to cause 20 the door sections to close tightly against the jambs, the carriers of the upper sections of the door will have their pintles 21 off-set a greater distance than those of the lower sections where the tracks are inclined more closely toward the 25 jambs.

The same result could be accomplished by cranking the pintles 21a as shown in Fig. 8, the throw or distance 21b of the cranks being decreased or increased according to the varied distances between the door jambs and the inclined tracks. Various other ways to obtain the same result are possible. Thus instead of varying the off-set of the pintles 21, the pins 20 and roller 19 could be off-set more or less in the respective carriers.

It is evident that as the door is closed down the incline of the track the various off-sets of the carriers will cause at the sections of the door to be forced into close contact with the jambs, thereby making a close and weather tight joint; and as the door is raised the sections will draw away from the jambs, thereby permitting easy operation.

For counterbalancing the door I provide a spring and cable device at each side of the doorway. Each cable 9 is connected at its lower end to the bottom door section and extends thence over a guide pulley 10, whose shaft 50 is supported by a frame 10a above the doorway, and thence downwardly to connection with a grooved and tapered sheave or drum 8 which runs free, for both rotary and axial movement, on a fixed shaft or rod 6 which is secured at one end to a 55

5 bracket 10b attached to the horizontal part of the track 7 and is secured at the other end to a fixture 10c projecting from the jamb. The rods 6 incline upwardly from the jambs to the tracks and thus also brace the upper part of the tracks. A spring 11 is coiled around each rod 6 and is fixed at one end to a collar 12 held to the rod by a set screw. The opposite end of the spring is fixed to the drum 8, which as stated, is free to rotate and 10 also slide on the rod 6.

10 As the door is lowered the drum 8 will be rotated by the cable and put the spring under tension which then assists in raising the door, and the axial movement of the drum accommodates the 15 contraction or expansion of the coiled spring and permits proper alignment of the cable as it winds or unwinds.

15 It will be seen that all the counterbalancing devices are located below or behind the track. This permits installation of the tracks nearer 20 the jambs and ceiling and is an advantage in

close quarters. Also by the use of two cables etc. and two pulleys 10 the cables operate jointly and prevent any sidewise strain or binding of the carriers in the tracks. Likewise strain is prevented by having the pulleys 10 securely fastened to the shaft 50 thus requiring the pulleys to travel together. Raising or lowering the door from either end will not tend to cause jamming but the door will remain in level position at all times. Various other advantages will be evident to those familiar with the art. 10

5 I claim:

A combined hinge bracket and roller carrier for sectional sliding doors, comprising a plate movable endwise with the door and having axle pins at one side and at opposite ends, rollers 15 mounted on the axle pins, and a hinge pintle pin projecting between the ends of the plate from the side thereof opposite the rollers.

20 GUY V. SMITH.
